APPARATUS FOR COVERING CORES

Oscar G. Nelson, Baltimore, Md., assignor to
Western Electric Company, Incorporated, New
York, N. Y., a corporation of New York

Application February 15, 1941, Serial No. 379,093

7 Claims. (Cl. 57—18)

This invention relates to apparatus for covering cores, and more particularly to apparatus for applying metal tape spirally to continuous cores, such as electric cables or the like.

Objects of the invention are to provide, in an apparatus of the aforementioned type, a simple, inexpensive and efficient serving head by means of which a metal tape or the like may be applied to a cable or the like uniformly and smoothly and with the required amount of tension at all times.

In accordance with one embodiment of the invention, there is provided a tape serving head having a tension controlling brake mechanism, which is influenced by centrifugal force to reduce the braking action on the tape supply roll as the taping head reaches its normal operating speed, the said brake mechanism being constructed and arranged so that its braking action diminishes as the diameter of the tape supply roll decreases.

A preferred embodiment of the invention is illustrated in the accompanying drawing, in which

Fig. 1 is an elevational view, partly in section, of a tape serving head embodying the features of the invention; and

Fig. 2 is an end view thereof, partly in section, looking in the direction of the arrows on line 2—2 of Fig. 1.

The serving head illustrated in the drawing comprises a rotary flier 10 consisting of a circular plate 11 having a concentric tubular hub 12 on one side thereof upon which a tape supply holder 14 is rotatably mounted. On its opposite side, the circular plate is provided with two diametrically opposed ears or lugs 15—15, by means of which it is attached by a yoke 16 to a tubular driving shaft 17 journalled in a suitable supporting frame or standard 18, a portion of which is shown in Fig. 1.

The tape supply holder comprises a circular plate 20 having a concentric tubular hub 21, which is rotatable on the hub 12 of the flier. A retaining collar 23 is attached to the end of the hub 12 to prevent axial displacement of the tape supply holder. This holder is adapted to hold a pad or roll 25 of metal tape 26. The roll of tape is placed upon the hub 21 of the holder and its tubular core is clamped against the plate 20 of the holder by means of a cylindrical retaining nut 28 threaded on the hub. The retaining nut has an outwardly extending circumferential flange 29, to which a series of radial arms 30, 30 are welded, which serve to hold the tape supply roll against the plate 20 as the tape is withdrawn from the roll. It is obvious, of course, that any other suitable means may be provided for holding the roll of tape on the tape supply holder.

Within the hub 12 of the flier 10, there is secured a tube 31, to which two diametrically op-

posed parallel rods 32—32 are attached. These rods support a sizing die holder 33, which is equipped with a sizing die 34. One of the rods also supports a tape guiding member 35, by means of which the tape is applied to a core or cable 37 at the desired angle as the cable is advanced through the rotating flier in the direction indicated by the arrow 38 in Fig. 1. The tape is guided from the supply roll to the guide 35 by two flanged rollers 39 and 40.

Secured to or formed integral with the tape supply roll holder 14 is a concentric brake drum 42, which is frictionally engaged by a brake shoe 43, as best shown in Fig. 2. The brake shoe is pivotally carried by an arm 44 keyed to a tubular shaft 45 (Fig. 1), which is rotatably journalled in a bearing 46 fixed to the flier 10 near its periphery. A shaft 48 is rotatably journalled intermediate its ends in the tubular shaft 45, and an arm 50 is attached at one end to one end of the shaft 48 and carries a roller 51 at its opposite end. This roller is adapted to ride on the periphery of the roll of tape, as best shown in Fig. 2. The roller is pressed against the tape roll and the brake shoe is pressed against the brake drum by a torsion spring 52 (Fig. 2) which is adjustable to vary the braking pressure in the manner hereinafter described.

A ratchet disk 53, having a hub 54, is keyed to the inner shaft 48 and a cooperating ratchet disk 56, having a hub 57, is rotatable on the hub of ratchet disk 53. The opposing faces of the two ratchet disks are provided with interlocking teeth 58, 58. The torsion spring 52 surrounds the hub 57 of ratchet disk 56 and is compressed between this ratchet disk and a flange 59 on tubular shaft 45. Ratchet disk 56 is thus pressed into interlocking engagement with ratchet disk 53, and since the latter is keyed to inner shaft 48, this shaft and roller carrying arm 50 are constrained to rotate with ratchet disk 56.

One end of torsion spring 52 is attached to ratchet disk 56 and its opposite end is attached to flange 59 of tubular shaft 45. The spring is tensioned so that it presses brake shoe 43 against brake drum 42 and also presses the roller 51 against the periphery of the tape supply roll. The braking pressure exerted by the spring may be adjusted by simply turning ratchet disk 56 relative to ratchet disk 53.

In the operation of the apparatus, the serving head is rotated around the advancing cable in the direction indicated by the arrow 60 in Fig. 2. The tape is thus drawn from the supply roll and spirally wrapped around the cable. At the beginning of the rotation of the serving head, the initial braking pressure exerted by the spring pressed brake shoe 43 on the brake drum 42 is sufficient to overcome the inertia of the tape supply roll and cause it to start rotating with the

flyer 18. Due to the action of centrifugal force on the brake shoe, the braking pressure exerted by the brake shoe on the brake drum decreases as the speed of rotation of the serving head increases. As the diameter of the tape supply roll decreases, the roller carrying arm 50 moves toward the axis of the serving head, as illustrated in broken lines in Fig. 2. This partially relieves or reduces the tension of the torsion spring 52, thereby reducing the braking pressure exerted by the brake shoe on the brake drum. Thus, the braking pressure decreases as the tape supply roll decreases in size, and since, as pointed out above, the braking pressure also decreases as the speed of rotation of the taping head increases, the tape is applied to the cable at a uniform tension at all times.

It should be understood that the invention is not limited to the particular embodiment thereof herein illustrated and described, but is capable of other applications within the scope of the appended claims.

What is claimed is:

1. In an apparatus for covering cores, a rotatable serving head, a holder rotatable on said head and adapted to support a supply roll of serving material, braking means responsive to the action of centrifugal force for opposing the rotation of said holder, and means responsive to reductions in the size of the supply roll for decreasing the effectiveness of said braking means.

2. In an apparatus for covering cores, a serving head mounted for rotation about an axis coaxial with a core to be covered, a covering material supply roll holder rotatable on said head about an axis coaxial with said head, a brake drum coaxial with said holder and rotatable therewith, a brake shoe responsive to the action of centrifugal force frictionally engaging said brake drum, and means responsive to reductions in the size of the supply roll for decreasing the pressure exerted by said brake shoe on said brake drum.

3. In an apparatus for covering cores, a serving head mounted for rotation about an axis coaxial with a core to be covered, a covering material supply roll holder rotatably mounted on said serving head, a covering material supply roll coaxially mounted on said holder and rotatable therewith, braking means mounted on the serving head for exerting a braking pressure on the supply roll holder, said braking means being responsive to the action of centrifugal force thereon for varying the braking pressure exerted thereby on said holder in accordance with variations in the rotating speed of the serving head, and means responsive to the decreasing size of the supply roll, as the material is withdrawn therefrom, for decreasing the braking pressure exerted by the braking means on said supply roll holder.

4. In an apparatus for covering cores, a serving head mounted for rotation about an axis coaxial with a core to be covered, a covering material supply roll holder rotatably mounted on said head coaxially therewith, a covering material supply roll coaxially mounted on said holder and rotatable therewith, braking means comprising a brake arm pivotally mounted on the serving head and adapted to exert a braking pressure on the supply roll holder, said brake arm being responsive to the action of centrifugal force thereon for varying the braking pressure exerted thereby on said holder in accordance with variations in the rotating speed of the serving head, and means responsive to the decreasing size of the supply roll, as the material is withdrawn therefrom, for decreasing the braking pressure exerted by the braking means on said supply roll holder.

5. In an apparatus for covering cores, a serving head mounted for rotation about an axis coaxial with a core to be covered, a covering material supply roll holder rotatably mounted on said head coaxially therewith, a covering material supply roll coaxially mounted on said holder and rotatable therewith, and braking means comprising a brake drum coaxially rotatable with said holder, a brake arm mounted on the serving head for exerting a braking pressure on said brake drum, said brake arm being responsive to the action of centrifugal force thereon for varying the braking pressure exerted thereby on said brake drum in accordance with variations in the rotating speed of the serving head, and means responsive to the decreasing size of the supply roll, as the material is withdrawn therefrom, for decreasing the braking pressure exerted by the brake arm on said supply roll holder.

6. In an apparatus for covering cores, a serving head mounted for rotation about an axis coaxial with a core to be covered, a covering material supply roll holder rotatably mounted on said head coaxially therewith, a covering material supply roll coaxially mounted on said holder and rotatable therewith, and braking means comprising a brake drum coaxially rotatable with said holder, a brake arm mounted on the serving head for exerting a braking pressure on said brake drum, said brake arm being responsive to the action of centrifugal force thereon for varying the braking pressure exerted thereby on said brake drum in accordance with variations in the rotating speed of the serving head, and means responsive to the decreasing size of the supply roll, as the material is withdrawn therefrom, for decreasing the braking pressure exerted by the brake arm on said supply roll holder.

7. In an apparatus for covering cores, a serving head mounted for rotation about an axis coaxial with a core to be covered, a covering material supply roll holder rotatably mounted on said head coaxially therewith, a covering material supply roll coaxially mounted on said holder and rotatable therewith, a brake drum coaxially rotatable with said holder, a brake arm pivotally mounted on the serving head for engagement with the brake drum, said brake arm being responsive to the action of centrifugal force thereon for varying the braking pressure exerted thereby on said brake drum, a follower arm pivotally mounted on the serving head coaxially with the brake arm and adapted to ride on the periphery of the supply roll, and a torsion spring interconnecting said brake arm and said follower arm for pressing the brake arm against the brake drum and for holding the follower arm against the supply roll.

8. In an apparatus for covering cores, a serving head mounted for rotation about an axis coaxial with a core to be covered, a covering material supply roll holder rotatably mounted on said head coaxially therewith, a covering material supply roll coaxially mounted on said holder and rotatable therewith, a brake drum coaxially rotatable with said holder, a brake arm pivotally mounted on the serving head for engagement with the brake drum, a spring for pressing the brake arm against the brake drum, said brake arm being responsive to the action of centrifugal force thereon for varying the braking force of the spring in accordance with variations in the rotating speed of the serving head, and a follower arm pivotally mounted on the serving head coaxially with the brake arm and held by the spring against the periphery of the supply roll so that the force of the spring decreases in accordance with the decreasing size of the supply roll as the material is withdrawn therefrom.

OSCAR G. NELSON,
